UNITED STATES PATENT OFFICE

J FORREST COBB, OF PORTLAND, OREGON, ASSIGNOR TO MOORE DRY KILN COMPANY, A CORPORATION OF FLORIDA

DRYING KILN

Application filed July 21, 1924. Serial No. 727,305.

My invention relates to improvements in kilns for drying different substances, but particularly lumber, by the application of a circulatory gaseous drying medium, either with or without use of artificial heat.

One object of my invention is to produce a kiln which is operative at all times, and exclusively if desired, by means of a gaseous drying medium circulated in the kiln simply upon the application thereto of heat derived from heating pipes disposed preferably in the lower part of the kiln, with provision of special means for effecting upward movement through the interior of the kiln of the drying medium from said pipes and back again thereto in constant circulation.

Another object of my invention is to produce circulation of the drying medium through the employment of a fan operatively communicating with the medium of circulation within the kiln. Said fan may be used to effect circulation either independently of or in conjunction with and as an auxiliary to the means of circulation described in the last preceding paragraph. I prefer, in employing such a fan, to locate it upon the outside of the kiln, and I make the kiln operative as by means of heat-compelled circulation without interfering in any way with the operation of the kiln independently of the fan, if it be desired so to operate it. Also the kiln may be operated by the fan to the exclusion of any other means of operating it, as well as by heat-promoted circulation without the aid of the fan.

Other objects of my invention will be apparent from the following specification in which what constitutes my invention is first described in detail and then succinctly defined in the appended claim.

Referring to the accompanying drawings, Figure I is a transverse vertical section of a kiln constituting one form of embodiment of my invention.

Figure II is a similar view of a kiln in a modified form of embodiment.

Figure III is a longitudinal vertical section as on the line III-III of Figure I, and extending the full length of the kiln.

Figure IV is a detached perspective view

of a fan and its ducts in present preferred form of embodiment of my invention as applied to the kiln shown in Figure I.

Figure V is a view similar to Figure IV showing a modified arrangement of such a fan and its ducts as is applicable to the form of kiln shown in Figure II.

Figure VI is a view similar to Figure I showing a fan-operated kiln of the type shown in Figure I.

Figure VII is a view corresponding to Figure VI but illustrative of a similar modification as applied to the subject-matter of Figure II.

Referring to the numerals on the drawings, 65 1 indicates an adequately fire-proof wall that is closed on all sides so as to form a kiln, and which may be made of any suitable and preferred design, material, and dimensions. The wall is penetrated, preferably at the opposite ends of the kiln, by the usual doors 13 70 constructed in any manner, either such as is usual in the art or as may be suitable and adapted for the purpose.

A construction of kiln that is well adapted 75 for my purpose is one made in whole or in part of concrete, and that construction may be regarded as the one illustrated in the drawings.

At any desired and convenient height 80 above the floor 2 of the kiln, I prefer to provide a succession of horizontal cross-beams 3, of such number, weight, dimensions, and distribution, as the size and capacity of the kiln may require. The cross-beams 3 are examples only of any suitable means of support for the material to be dried. To that end I prefer to provide upon them parallel track rails 4 and 5, extending through the kiln from end to end, and adapted for the 85 support and operative accommodation of wheeled trucks 6, which carry an open car platform 7 made of open spaced separate cross-bars upon which is loaded the substance to be dried. Two opposite pairs of 90 trucks 6 and their respective cross-bars uniting them may constitute in effect a car platform, the load upon the cross-bars serving of itself to operatively unite the cross-bars.

In Figure I, the substance to be dried is 100

represented by a stack 8 of lumber piled edge-wise, with spaces 9 between the boards wide enough for the proper circulation through them of a gaseous drying medium. Suitable means for confining the load upon the car platform are of course contemplated, and are represented in Figure I by side stakes 10 united at their tops by tie-stays 11, for example.

10 In Figure II, I illustrate a load 12 of boards piled sidewise upon the car platform 7, with horizontal spaces 14 between the boards for the circulation through them of the drying medium, and built so as to define, for instance, 15 a capped medial chimney 15 extending, in effect, the full length of the kiln-charge, and formed in a manner well known in the art by one method commonly employed in the piling of lumber.

20 The illustration of the two modifications of my invention shown by way of example in Figures I and II, is offered for the purpose of clearly indicating a breadth of scope of my invention intended.

25 In Figure I, I show two baffle-plates 16 and 17 located towards opposite sides of the kiln and comprising divergent sections 18 and 19, respectively, joined thereto along their upper edges, and in turn surmounted, respectively, by substantially vertical plates 20 and 21. The baffle-plates in any form of embodiment extend the full length of the kiln substantially, so as to constitute in effect division walls for effecting operative circulation of 30 the drying medium within the kiln. The several parts of each baffle-plate constitute, in effect, one member. They are preferably combined in one integral structure, in all instances, and may likewise be made of metal, 35 concrete, or any suitable material.

40 The plates 20 and 21 if employed, as they preferably are, or otherwise the upper edges of the members 18 and 19 of the baffle-plates, extend substantially the full width of the platform 7, so as to define a flue extending the full length of the kiln below the track rails 4 and 5 for properly directing movement of the circulatory drying medium, ample spaces for the circulation of the drying medium being provided between the lower edges 23 of the baffle-plates 16 and 17 and the floor 2 of the kiln.

45 Within the space defined between the lengths of the baffle-plates 16 and 17 and the opposite side walls of the kiln, respectively, I provide, in such a device as is shown in Figure I, two systems or coils of heating pipes 24 and 25, which may be made of preferred arrangement of pipe sections in co- 50 operative assemblage and spaced apart for passage between them of the gaseous circulatory medium. The respective coils 24 and 25 make operative communication with any ordinary source of heat located outside the kiln, and unnecessary to illustrate. The

55 pipes of the respective heating coils may be carried on cross-supports 27 sustained by pipe-hangers 28, but this is only an example of preferred structural details.

Above each of the coils 24 and 25, respectively, I prefer to provide an accelerator pipe 30 which extends substantially the entire interior length of the kiln, and which is provided along its length with a row of upwardly discharging orifices through which a blast of heated air or a spray of steam may be discharged with the effect of accelerating, or of both accelerating and humidifying the passing circulatory medium. A corresponding, downwardly discharging, accelerator pipe 31 may be used to advantage between the baffle-plates 16 and 17, where it may be conveniently carried, for instance, upon the topmost row of cross-supports 27. I also prefer to provide along the top of the kiln, at required intervals, ventilators 32, which may be of any suitable form preferred.

60 The description of the heating apparatus above specified is that shown in Figures I and III of the drawings, and is adapted to provide within the kiln a downward circulation of air through the material to be dried that is loaded upon the cross-bars of the car platform 7. In that case separate currents of the circulatory medium pass upwardly 65 along the opposite sides of the kiln, as shown by arrows in Figure I.

65 In Figure II, I show a heating means corresponding substantially in form and function to that shown in Figure I, with this variation, that in Figure II, baffle-plates 35 and 36 are employed which flank a single heating coil 37 and partially cover it with roof-like sections 38 and 39. The baffle-plate sections 38 and 39 are separated between their opposing horizontal edges 40 by a space substantially equal in width to that of the bottom of the longitudinally extended chimney 15. In Figure II, also, I show lateral downwardly discharging accelerator pipes 41 and 42, and an upwardly discharging medial accelerator pipe 43, said pipes corresponding in function to the accelerator pipes 30 and 31 already specified. Accelerator pipes of the type just indicated may be multiplied in number, if desired, and located wherever they may be disposed to advantage.

70 The difference in the heating system shown and described with respect to Figure I and that shown and described with respect to Figure II is this, that while the heating coils of both systems establish an upward movement of the gaseous heating medium through them, the location of the two heating coils upon the outside of the baffle-plates 16 and 17 effects an upward movement of the circulatory medium along the sides of the kiln and a downward movement thereof through the body of the material to be dried, whereas, 75 in Figure II the movement of said medium 80

directed from the single coil 37 causes circulation of the circulatory medium vertically and laterally through the chimney 15, and then downwardly along the opposite sides of the kiln. The result in each instance is substantially identical in respect to the drying operation, the one system lending itself most advantageously to the edgewise method of lumber piling, and the other to the sidewise method of lumber piling.

Having described my kiln in respect to its two methods of heating the same, I come now to description of means contemplated for promoting circulation of the drying or heating medium within the kiln, either in conjunction with or without heating appliances, through the employment of a fan indicated, for example, in Figures IV and V, respectively. The means illustrated in the former is applicable to the form of kiln shown in Figure I, and that illustrated in the latter, to that shown in Figure II. In Figure I, I illustrate in cross-section, below the floor 2 and between it and the bottom wall 45 of the kiln, three ducts separated as by partition walls 46 and 47. The medial duct 48 therein is the return duct, and the lateral ducts 49 and 50 are the delivery ducts. Each duct extends substantially the full length of the interior of the kiln, and each is brought into operative communication, at one end, with a fan-case 53 representative of a power driven fan or fans. In Figure IV the ducts 49 and 50 unite, as indicated at 51, so as to communicate, respectively, with the fan-discharge, and the duct 48 operatively communicates with the fan-intake. In Figure IV, also, the ducts 48, 49, and 50, are shown as made, for example, of metal and separable from the kiln upon the outside of which the fan-case 53 is preferably located. This construction is entirely practicable, but it should be understood that the fan may be operatively connected directly with ducts formed in the material of the kiln itself instead of being made of separable metallic members insertable into the same. The ducts 48, 49, and 50, are preferably in effect constricted for pressure equalization purposes, preferably by being tapered, towards their ends opposite the fan-case 53. Their ends next to said case should be of an area in cross-section substantially equal to the fan-intake and discharge openings, respectively, while their opposite ends may vary in area of cross-section according to variable determining factors. Along the length of each duct is provided a series of apertures 54 equipped with ordinary upwardly directing deflectors if desired, which open upwardly into the kiln through corresponding apertures provided in the floor 2, in case the floor and the duct employed are separate elements.

The construction shown in Figure V is substantially the same as that shown and de-

scribed in Figure IV, with the one exception that in the arrangement illustrated in Figure V, it being applicable to the form of kiln shown in Figure II, two return ducts 55 and 56 and a single delivery duct 57 are provided instead of the two delivery ducts and one return duct shown in Figure IV.

The precise location of the delivery and return ducts, in any form of arrangement of them which may be employed, is not limited to disposition underneath the floor 2. On the contrary they may be disposed anywhere within the kiln where they may functionate to advantage in substantially the same manner in which they functionate in their respective dispositions herein illustrated and described. Also, the return and delivery ducts, respectively, may be ramified to any extent desired if it be found advantageous to divide any or all of them into branches.

The modification shown in Figure VI simply consists of extension of the respective baffle-plates 16 and 17 of Figure I to the floor 2 of the kiln with the effect of closing the openings shown in Figure I between the lower edges 23 of said baffle-plates and the floor. The baffle-plates so extended, as shown in Figure VI, are distinctively indicated by reference numerals 61 and 62.

Figure VII shows the baffle-plates 35 and 36 of Figure II downwardly extended in like manner and with similar effect to what is shown in Figure VI. The extended baffle-plates in Figure VII are indicated for distinction by reference numerals 63 and 64, respectively.

The operation of my invention may be, in view of the foregoing, described as follows. In respect to its embodiment shown in Figure I, the heating coils 24 and 25, when heated, serve by rarefaction of the air within the kiln, to lift the air above them. That movement causes the air by compression of it above the lumber pile 8 and by the cooling of it due to evaporation of moisture from the lumber in the drying operation, to descend through the spaces provided through it in the piling, and to drive the air out from between the baffle-plates 16 and 17 below the edges 23 thereof. The effect will be to produce a constant circulation of heated air and its accumulated gaseous additions constituting the circulatory heating medium, in the direction of the arrows shown in Figure I.

The means just described are sufficient to effect the drying of the contents of the kiln, and, for some purposes, that drying means is all sufficient. If, however, a more rapid drying effect is desired, as occasion may demand, the fan 53 may be brought into requisition at any time as an auxiliary means of circulation. It should be observed, however, that the kiln is at all times operable independently of the fan, and that the interruption of the operation of the fan, through accident,

for example, will, in such case, only serve to retard but not to interrupt the effective drying operation of the kiln. Also it is entirely feasible to operate the kiln for drying purposes by aid of the fan exclusively, and without application of artificial heat. In fact for drying certain substances, or under certain climatic conditions, it is desirable at intervals of operation, or even in some instances altogether, to dispense with artificial heat. In such cases the drying capacity of the circulatory medium without the aid of artificial heat, may be, by proper attention to humidification, relied upon to effect the drying operation desired. Under such conditions the fan becomes an element of prime importance in my invention.

With respect to the kiln shown in Figure II, little description of operation in addition to what has been already specified is necessary. Repeating that the heating coil 37 effects an upward movement of air through the chimney 15, thence laterally through the lumber pile 12, and thence downwardly along the sides of the kiln, as shown by the arrows, it is deemed sufficient to explain that in Figure I there are two heating coils instead of the one in Figure II. The substitution of two return ducts to the fan as shown in Figure II, for the one return duct as shown in Figure I, accomplishes in effect the same result for the single medially located coil 37 as that accomplished in Figure I for the two heating coils 24 and 25, with reversal only of the direction of circulation of the heating medium.

In the modifications of my invention shown in Figures VI and VII, respectively, circulation may be effected by aid of the fan either with or without the aid of the respective heating coils 24 and 25, or the single coil 37. It should be observed, however, that in such case the entire volume of the drying medium is caused to pass through the fan-case 53 in order to effect complete circulation, while in the kilns shown in Figures I and II it is necessary to draw off through the fan-case only a portion of the entire volume of the drying medium in effecting its circulation. Besides the portion of the drying medium drawn directly through the fan-case, other portions thereof will be, by induced circulation, kept stirring and secure against stagnation anywhere within the kiln.

In the description of my invention hitherto, the fan has been assumed to be operative so as to promote only currents of the circulating medium flowing in the same direction with such flow of the circulatory medium as would be effected by the presence and functioning of the heating coils aforesaid. It is important to note, however, that it is desirable, under some conditions, to reverse the direction of rotation of the fan, with the result of reversing the direction of movement

of the circulatory medium, even against the tendency of movement imparted to it by the functioning of the heating coils alone. The result so obtained may be, under varying conditions, distinctly advantageous whether the fan is used in conjunction with the heating coils or not. Therefore the potential reversibility of the fan in combination with its cooperative elements is regarded as a feature of my invention of no minor importance.

What I claim is:

In a drying kiln, the combination with enclosure-defining walls, of means for causing continuous circulation of a gaseous drying medium within said enclosure, said means consisting of air delivery and return ducts, and fan mechanism in operative communication therewith, respectively, said ducts consisting of metallic members separably insertable into openings provided in said enclosure for their reception.

In testimony whereof, I have hereunto set my hand.

J FORREST COBB.
